(57) **CLAIM**

The ornamental design for a baseball, as shown and described.

DESCRIPTION

FIG. 1 is a perspective view of a baseball;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof; and,

FIG. 8 is another perspective view thereof.

The broken lines of the stitches in the drawings form no part of the claimed design and the broken lines of the throwing hand of FIG. 8 are illustrative of environment and form no part of the claimed design.

1 Claim, 8 Drawing Sheets
